(57) **CLAIM**

The ornamental design for an electrical connector, as shown and described.

DESCRIPTION

The present application is related by subject matter to U.S. provisional patent application Ser. No. 61,437,533 filed Jan. 28, 2011; U.S. design patent application Ser. No. 29,384,319 filed Jan. 28, 2011; and U.S. design patent application Ser. No. 29/384,322 filed Jan. 28, 2011.

FIG. 1 is a top, right, front perspective view of an electrical connector according to my design;

FIG. 2 is a bottom, left, rear perspective view thereof;

FIG. 3 is a top plan view thereof;

FIG. 4 is a front elevation view thereof;

FIG. 5 is a bottom plan view thereof;

FIG. 6 is a rear elevation view thereof

FIG. 7 is a left side elevation view thereof; and,

FIG. 8 is a right side elevation view thereof.

The broken line portion of the figure drawings is included for the purpose of illustrating environment and forms no part of the claimed design.

In a preferred embodiment, the nature of this product is an electrical connector configured for electrically connecting to an electrical device.
